HEATING SYSTEM

Henry J. De N. McCollum, Chicago, Ill.; Thelma McCollum, executrix of said Henry J. De N. McCollum, deceased

Application February 3, 1941, Serial No. 377,181

5 Claims. (Cl. 126—110)

My invention relates generally to heating systems particularly suited for use in heating large conveyances such as airplanes, trucks, buses, Diesel operated trains, and the like.

Considerable difficulty has been experienced in devising a heating system to heat the cabins of airplanes and maintain them at a uniform temperature under the greatly varying conditions of airplane operation. In most previous heating systems used for this purpose, the engine exhaust gases have been used as a source of heat. In general, two types of systems are used. In the first, the exhaust gases are passed through a heat exchanger which directly heats the air passing into the cabin, and in the second, the exhaust gases are used to vaporize a liquid to form a vapor which is used to heat the air passing into the cabin. In these previous systems, the amount of heat available varies widely and is greatly reduced when the engine is throttled down as in a long glide. Further, these heating systems are inoperative while the plane is on the ground loading or unloading, and it is necessary to use an independent source of heated air if the passenger compartment of the plane is to be heated while it is at the airport.

An object of my invention is to provide an improved, independently operated heating system for airplanes in which the above disadvantages are eliminated.

Another object of my invention is to provide an improved internal combustion heating system for airplanes and the like which burns liquid fuel independently of the airplane motor, which is easily controlled to maintain a uniform temperature in the airplane cabin, which is simple in construction, which may be easily installed, and which is compact, light in weight, and reliable in operation.

A further object is to provide an internal combustion heating system for airplanes and the like which will supply a large volume of air heated to a uniform temperature.

Other objects will appear from the following description, reference being had to the accompanying drawings, in which:

Fig. 1 is a diagrammatic representation of the general arrangement of the various elements which comprise a form of my invention;

Fig. 2 is a partially cross-sectional diagram of a modified form of my invention, particularly adapted for use in heating a supercharged airplane cabin;

Fig. 3 is a diagrammatic representation of a form of my improved heating system in which

the combustible mixture used in the heating system may be supplied either by the supercharger of the airplane engine or by a separate heater carburetor;

5 Fig. 4 is a perspective drawing of a heater which may be used in connection with the heating systems represented in Figs. 1, 2, and 3, and

Fig. 5 is a transverse sectional view taken on the plane 5—5 of Fig. 4, illustrating the construction of a heating unit suited for use in the heater illustrated in Fig. 3.

Referring to Fig. 1, a source of power 10, preferably a light, compact, air-cooled, single cylinder internal combustion engine, drives a centrifugal blower 14 for forcing air through the heater 34 into the space to be heated and an air pump or blower 12, which may be of the positive displacement type, for supplying a combustible mixture of liquid fuel and air to the engine 10 and the internal combustion heater 34. Fuel is supplied from a fuel supply 20, through a fuel line 18, to a carburetor 16 which mixes fuel and air in the proper proportions to form a combustible mixture. Combustible mixture is drawn from the carburetor 16, through a conduit 19, into the blower 12 where it is compressed. A by-pass conduit 24, provided with an adjustable valve 26 to control the rate of flow therethrough, connects the inlet and outlet of the blower 12. The 15 compressed combustible mixture passes from the blower 12, through a conduit 22, and through conduits 32 and 28, to the heater 34 and the internal combustion engine 10, respectively. Adjustable valves 30 and 36 in conduits 32 and 28 20 may be regulated to control the rate of flow of combustible mixture through these conduits, respectively, to deliver combustible mixture to the engine 10 and heater 34 in the proper proportion to heat the air passing through the heater to the desired temperature.

Air passes from the atmosphere into the centrifugal blower 14 where it is compressed and supplied to the inlet of the heater 34 through a conduit 38. A conduit 40, leading from the outlet of the heater 34, conveys heated air to the cabin of the plane. This conduit 40 is preferably branched to distribute the heat properly through the space to be heated. A pipe 44 conveys the exhaust gases of the engine 10 to the atmosphere. The products of combustion from the heating unit 34 are discharged through a conduit 42 which preferably terminates at a point adjacent the outer surface of the plane where the pressure is maintained below atmospheric pressure by the motion of the plane.

It is seen from the above arrangement that the rate at which combustible mixture is drawn from the carburetor may be controlled by adjustment of the valve 26. If the flow through the valve 26 is decreased, less combustible mixture passes through the by-pass 24 and more combustible mixture is supplied to the heater 34 and the engine 10. This causes the engine 10 to operate the blower 14 at a greater speed to pass more air through the heater. Inasmuch as more combustible mixture is supplied to the heater, the heater delivers more heat to the air passing through it and the resulting temperature of the air in the conduit 40 remains relatively constant. Conversely, increasing the rate of flow through the valve 26 decreases the amount of air heated but does not substantially change the temperature thereof. From the foregoing, it is seen that the amount of heat supplied to the cabin may be adjusted by varying the rate that heated air passes into the cabin rather than by raising or lowering the temperature of the heated air. Therefore there is no danger of overheating the various parts of the heater assembly and an occupant of the cabin of the plane seated near a hot air outlet is not subjected to the discomfort of having an uncomfortably hot blast of air blown upon him.

In the embodiment shown in Fig. 2, a small, light gasoline engine 102 drives a cycloidal blower 100 of sufficient capacity to supercharge the airplane cabin. One end of the crank shaft is provided with a pulley 108, around which a cord may be wound to crank the engine, and is connected to the shaft of the blower 100 by a flexible coupling 106. The other end of the motor shaft is provided with a small blower 104 which blows cooling air past the finned cylinder of the engine 102. The blower 100 draws air from the atmosphere, compresses it, and forces it through a conduit 110 to the inlet of the heater casing 112. A conduit 120 supplies air under pressure from the outlet of the blower 100 to the inlet of a balanced carburetor 122. A compensating duct 126 connects the conduit 120 with the float bowl of the carburetor 122 to equalize the pressure thereon. Combustible mixture passes from the outlet of the carburetor through a conduit 130 and through a pair of intake manifolds 132 to the individual heating units 134. A conduit 135, provided with an adjustable valve 137 for regulating the rate of flow therethrough, supplies combustible mixture from the outlet of the carburetor 122 to the engine 102.

The products of combustion from the heating units 134 pass into a pair of exhaust manifolds 116, which conduct them to an exhaust pipe 118 which discharges them, preferably at a point adjacent to the outer surface of the airplane maintained at subatmospheric pressure by the motion of the plane. The engine exhaust discharges through an exhaust pipe 139, which is provided with a silencer 142, into the atmosphere.

An apertured plate 136, located in the casing outlet conduit 138, is proportioned to maintain a sufficient back pressure in the conduit 110, that in the event of any leakage in the heating units, the combustible mixture and the products of combustion therefrom will not escape to the air being heated. A pressure responsive valve of the type disclosed in my copending application Serial No. 373,751, filed January 9, 1941, may be substituted for the apertured plate 136. The conduit 138, which conveys the heated air to the

5 cabin of the plane, is preferably branched to secure an even distribution of heat.

A butterfly valve 150, located in the conduit 130, directly controls the rate of flow of combustible mixture into the heating units 134. The valve 137 in the conduit 135 controls the rate of combustible mixture supplied to the engine 102. By proper relative adjustment of the valves 137 and 150, the relative amounts of combustible mixture flowing through the conduits 135 and 130 may be regulated to heat the air passing from the heater to the desired temperature. The resistance of the various conduits may be so proportioned that the capacity of the conduits supplying combustible mixture to the heating units bears the proper relationship to the capacity of the conduits supplying combustible mixture to the engine, and either or both of the valves 150 and 137 may be eliminated. A check valve 148 is preferably provided in the conduit 120 to prevent backfiring of the combustible mixture and the products of combustion into the air being heated.

A second butterfly valve 148 controls the rate of flow of air through the conduit 120 and thereby controls the rate at which combustible mixture is supplied to both the heater and the engine. Adjustment of the valve 148 does not affect the relative proportions of the amounts of combustible mixture supplied to the engine and to the heater. Thus, as valve 148 is closed to reduce the amount of combustible mixture supplied, the engine will operate the blower 100 more slowly and air will be passed through the heater more slowly. The amount of combustible mixture burned in the heater will be correspondingly reduced and the net result will be that the air passing through the heater will be heated to substantially the same temperature for all adjustments of the valve 148.

30 The heating system illustrated in Fig. 3 is much the same in construction and operation as the heating system shown in Fig. 1. Illustrated in connection with the heating system is an airplane engine 158 having a supercharger and a supercharger casing 156. Combustible mixture is drawn by the supercharger from the airplane carburetor 160 into the supercharger casing 156 where it is compressed. A manually operable three-way valve 150 controls the admission of combustible mixture to the inlet conduit 18 of the blower 12. When the airplane is cruising, this valve may be positioned to supply combustible mixture under pressure from the supercharger casing 156 to the inlet of the blower 12. 45 When the airplane engine is not in operation, or when it is idling, the three-way valve 150 may be positioned so that the blower 12 draws combustible mixture through a conduit 154 from the heating system carburetor 16. Other portions of 50 the apparatus correspond to similar portions described in connection with Fig. 1, and are similarly numbered.

55 When the airplane is operating at high altitudes, it is advantageous for the pressure of air passing through the heater and the combustible mixture passing into the heater to be greater with respect to atmospheric pressure than when the plane is operating at lower altitudes, so that the air in the airplane cabin is somewhat supercharged. This causes a greater load to be imposed upon the engine 10, inasmuch as the blower 14 and the pump 12 operate at a greater pressure differential between their respective inlets and outlets. However, by positioning the valve 150 to supply combustible mixture under pressure from the air-

plane supercharger to the heating system, the load upon the pump 12 is substantially eliminated. The engine 10 will then run faster and cause the blower 14 to supply air to the cabin at a greater pressure. The amount of combustible mixture used in the heating system is so small in relation to the amount of combustible mixture burned in the engine that the operation of the heating system has no detectable effect upon the performance of the airplane engine.

Referring to Figs. 4 and 5, Fig. 4 is a perspective view of a heater, comprising two series of heating units, adapted for use in my improved heating system, and Fig. 5 is a cross-sectional view of the heater along the plane 5—5 of Fig. 4, showing one of the heating units in vertical cross-section. Each heating unit comprises a flanged casting 52 which extends through the casing 50 of the heater and is secured thereto by screws 94, thereby holding the unit in its proper position. Combustible mixture is supplied to fittings 88, each fitting distributing the mixture to one series of heating units. Combustible mixture passes from these fittings 88, through tubes 90, to the individual heating units. The tubes 90 are preferably of equal length and diameter so that they have equal resistance to fluid flow and therefore supply equal quantities of combustible mixture to the various units.

The individual heating units may be of the general type disclosed in my prior Patents Nos. 2,191,173, 2,191,174, and 2,191,178, issued February 20, 1940. The casting 52 comprises a generally cylindrical bore 53, the walls of which are protected by a cylindrical liner 56 of a heat and corrosion resistant material, such as stainless steel or a ceramic composition, to form a combustion chamber 52. Combustible mixture flows from the tube 90, through an elbow-shaped passageway 64 formed in the projecting portion 66 of the casting 52, into a burner tube 62 which contains a loose packing 64 of metal wool. From the burner tube 62 the mixture flows past peripheral ports 58 formed in a baffle 60, which forms the inlet end wall of the combustion chamber 52, into the combustion chamber 52 where it is burned. An apertured ceramic plug 68, which serves as a reigniter in a manner more fully disclosed in my prior Patent 2,192,688, issued March 5, 1940, is located in the outlet of the combustion chamber. A heat exchanger casting 76, having interconnected circuitous passageway 74 formed therein, receives the products of combustion from the combustion chamber 52. A copper shell 76, provided with heat exchange fins 80, encloses the portion of the heating unit within the casing 50 and retains the heat exchanger casting 76 to the flanged casting 52. The products of combustion pass from the outlet 96 through the circuitous passageways 74 into the heater exhaust manifolds 116.

As shown in Fig. 4, the heating units may be arranged in two series of five units each, there being ten units in all. One electrically operated igniter 84, which may be of the type disclosed in my prior Patent No. 2,177,114 issued October 24, 1939, is provided for each series of units. The igniter is positioned to ignite the combustible mixture and start combustion in the end heating unit of the series. The combustion chambers are interconnected by flash-over tubes 70 through which flame travels from the combustion chamber of one unit to the combustion chamber of the next unit of the series. A thermostatic switch 72 is provided to control the energization of each igniter. These switches are electrically connected in

series with the live terminal 95 of each igniter, the other terminal being grounded. The switches 72 are closed at lower temperatures, but are responsive to the temperature of the heater to open the igniter circuits when combustion has been established, thereby discontinuing the energization of the igniters 84. A manually operable switch 92, in series with the thermostatic switches 72, connects and disconnects a source of electric current 93 and the igniter circuit. This switch 92 is preferably arranged to be opened and closed incidental to opening and closing the ignition switch of the gasoline engine which operates the system.

In the operation of the system shown in Fig. 1, the engine is cranked and combustible mixture is drawn from the carburetor 16 by the pump 12 and supplied to the engine 10 where it is burned to supply power to operate the system. The starting of the engine 10 is facilitated if the valves 26 and 30 are closed. The engine 10 operates the blower 14 which draws air from the atmosphere and forces it through the heater 34 and through the conduit 40 to the space to be heated. The pump 12 also supplies combustible mixture through the conduit 32 to the heater 34 where it is burned to supply heat which heats the air passing through the heater. The products of combustion from the engine 10 and the heater 34 pass through conduits 44 and 42 respectively and are discharged at a convenient point, preferably adjacent the outer surface of the plane where the pressure is maintained below atmospheric by the motion of the plane.

In the operation of the device shown in Fig. 2, the engine is cranked to operate the cycloidal blower 100. The blower 100 draws air from the atmosphere, compresses it, and passes it to the balanced carburetor 122 where it is mixed with fuel to form a combustible mixture. The combustible mixture then flows from the carburetor 122, through the conduit 135, to the engine 102 where it is burned to provide power to operate the blower 100. The starting of the engine 104 will be facilitated if the valve 150 is closed. Air compressed by the blower 100 also passes through the heater 34 and through the conduit 138 to the cabin of the plane. Part of the combustible mixture from the balance carburetor 122 is supplied to the heating units 134 of the heater 34 where it is burned to heat the air passing through the heater 34. The pressure of the air within the heater 34 is maintained at a positive pressure with respect to the interior of the heating units 134 by suitable means, illustrated as an apertured plate 136 in the conduit 138. The products of combustion from the engine 102 and the heater 134 are discharged through conduits 139 and 143 respectively.

The embodiment shown in Fig. 3 operates in a manner similar to the embodiment shown in Fig. 1 and described in connection therewith. However, at high altitudes, it will be found advantageous to operate the three-way valve 150 so that combustible mixture is supplied to the heating system from the casing 158 of the supercharger of the airplane engine.

In the operation of the heater 34, shown in Figs. 4 and 5, the igniter 92 is closed to energize the igniter 84. Combustible mixture under pressure is supplied to the fittings 88 from which it passes through tubes 90 to the combustion chambers 52 of the individual heating units. The igniter 84 in the end unit of each series starts combustion in the combustion chamber of that unit. Flame

then rapidly flashes through the flashover tubes 18 and establishes combustion in the interconnected heating units of the series in rapid succession. The products of combustion flow from each combustion chamber 52, through ports 69 in each ceramic plug 68 into the circuitous passageways 14, heating the heat exchanger casting 16 which, in turn, conducts heat to the exchange fins 80. The air passing through the heater comes into contact with these heat exchange fins and is heated. The products of combustion pass from the interconnected passageways 14 into exhaust manifolds 116 and through an exhaust pipe to the atmosphere. It is to be understood that a different form of internal combustion heating unit may be substituted in the heater for the one specifically described above.

While I have shown and described particular embodiments of my invention, it will be apparent to those skilled in the art that my invention is not limited to particular constructions disclosed. I, therefore, wish to include within the scope of the following claims all constructions by which substantially the results of my invention are obtained by substantially the same or equivalent means.

I claim:

1. In a heating system for airplanes and the like, the combination of an internal combustion heater having an air inlet and outlet and burning a combustible mixture of vaporized fuel and air, an internal combustion engine, a source of air, a blower driven by said engine to compress air from said source, a fuel supply, carbureting means receiving fuel from said supply and mixing it with air to form a combustible mixture, a passage for conveying air under pressure from the outlet of said blower to the inlet of said heater, a passage for conveying heated air from the outlet of said heater to the space to be heated, a passage to supply air under pressure from the outlet of said blower to the inlet of said carburetor, a passage for conveying combustible mixture from said carburetor to said heater, and a passage for conveying combustible mixture from said carburetor to said engine.

2. In a heating system for airplanes and the like, the combination of an internal combustion heater having an air inlet and an outlet and burning a mixture of vaporized fuel and air, an internal combustion engine, a source of air, a blower driven by said engine for compressing air from said source, a fuel supply, carbureting means for mixing fuel from said supply with air to form a combustible mixture, a passage for supplying compressed air from the outlet of said blower to the inlet of said heater, a passage connecting the outlet of said heater to the space to be heated, a passage for supplying compressed air from the outlet of said blower to the inlet of said carburetor, a valve for regulating the rate of flow

through said last named passage, a passage for supplying combustible mixture from said carburetor to said heater, and a passage for supplying combustible mixture from said carburetor to said engine.

3. In a heating system for airplanes and the like, the combination of an internal combustion heater having an air inlet and outlet and burning a mixture of vaporized fuel and air, an internal combustion engine, a source of air, a blower driven by said engine for compressing air from said source, a fuel supply, carbureting means for mixing fuel from said supply with air to form a combustible mixture, a passage for supplying air under pressure from said blower to said heater, a passage for conveying heated air from the outlet of said heater to the space to be heated, a passage for supplying air under pressure from said blower to said carburetor, a check valve to permit air to flow from the blower to the carburetor and to prevent air from flowing in the reverse direction, a passage for supplying combustible mixture from said carburetor to said heater, and a passage for supplying combustible mixture from said carburetor to said engine.

4. In a heating system for airplanes and the like, the combination of an internal combustion heater burning a combustible mixture of fuel and air therein, a fuel supply, a source of air, a carburetor receiving fuel from said supply and mixing it with air to form a combustible mixture, an internal combustion engine, a passage for conducting combustible mixture from said carburetor to said heater, a passage for conducting combustible mixture from said carburetor to said engine, and means driven by said engine to pass air from said source through said heater to be heated thereby and to supply air under pressure to said carburetor.

5. In a heating system for airplanes and the like, the combination of an internal combustion heater burning a combustible mixture of vaporized fuel and air, an internal combustion engine, a source of air, a blower driven by said engine for compressing air from said source, a fuel supply, carbureting means receiving fuel from said supply and mixing it with air to form a combustible mixture, a duct for conveying air under pressure from said blower to said heater, means for distributing the air heated by said heater into the space to be heated, a duct to supply air under pressure from said blower to the inlet of said carbureting means, a duct for supplying combustible mixture from said carburetor to said heater, a duct for conveying combustible mixture from said carburetor to said engine, and means for controlling the relative amounts of combustible mixture supplied to said heater and said engine, whereby said system may be caused to deliver air heated to the desired temperature.

HENRY J. DE N. McCOLLUM.
